10 Claims. (Cl. 315—3.5)

This invention relates to microwave tubes and more particularly to means for focusing a hollow electron stream of a traveling-wave tube.

A type of traveling-wave tube oscillator called a backward-wave oscillator is well-known. In this oscillator it is conventional practice to project a hollow electron stream contiguous to a periodic slow-wave structure to cause interaction of an electromagnetic wave propagated along the structure and this stream. A hollow instead of a solid electron stream is employed to attain optimum efficiency. Further, in order to effect maximum interaction of the stream and the wave, it is desirable that the stream be projected as close to the slow-wave structure as it is physically possible. However, an appreciable number of electrons collide with the slow-wave structure whereby the efficiency of the oscillator is materially reduced. In order to produce collimation of electrons in the hollow stream, a solenoid is normally positioned concentrically about the stream to produce an axial magnetic field which constrains or confines the stream.

The employment of a solenoid in a traveling-wave tube is one of the outstanding disadvantages of the backward-wave oscillator in that the solenoid is relatively bulky and heavy and requires a considerable amount of direct current power.

Furthermore, a hollow electron stream cannot be accurately focused simply with the use of a system of magnetic lenses of the conventional type because the inner surface of the focused stream tends to collapse, so that a relatively large number of electrons on the inner boundary surface of the hollow stream have trajectories which prevent them from interacting with the electric fields of the electromagnetic wave. Efficiency is consequently reduced still further.

An object of the invention is therefore to provide means whereby a hollow electron stream may be properly focused through substantially its entire length.

Another object of the invention is to provide an improved focusing system for the hollow electron stream of a traveling-wave tube oscillator whereby the stream may be focused through substantially the complete length of the tube.

In accordance with the present invention a plurality of magnetic electron lenses are provided at periodic intervals along a hollow electron stream, the direction of the axial magnetic field of the lenses being in one direction within a predetermined radius and being in the opposite direction outside of that predetermined radius. The lens fields and the beam perveance are then adjusted to balance the inward magnetic force against the outward centrifugal and space charge forces of the electrons. The outer boundary surface of the hollow stream is then focused toward a point between the lenses. The magnetic flux density produced at the predetermined radius is equal to zero in the longitudinal center of the lens and the hollow stream is introduced into the field of the first electron lens in a manner to cause the inner boundary surface of the hollow stream to be focused outward toward the same

points as the outer boundary surface, the predetermined radius falling within the maximum deviation of the inner boundary surface.

The above and other objects of the invention will become apparent from the following description taken in conjunction with the accompanying drawing made a part of this specification. In the drawing:

Fig. 1 is a sectional view of an oscillator embodying the present invention;

Fig. 2 is a diagrammatic sectional view of the electron stream employed with the oscillator of Fig. 1; and

Figs. 3 and 4 are sectional views of alternative lens structures of the invention.

Referring to the drawing, a backward-wave oscillator 15 is shown in Fig. 1 comprising a traveling-wave tube 10 including an evacuated envelope 12 having an enlarged portion 14 at its left extremity, as viewed in the drawing. In the enlarged envelope portion 14 an electron gun 13 is shown comprising a hollow cylindrical cathode 16 which is disposed about a longitudinal dielectric rod 18, a cathode heater 20, internal and external focusing electrodes 22 and 24, and an accelerating anode 26. Dielectric rod 18 may be made of glass or a number of dielectrics, e. g., those known commercially as synthetic 25 sapphire and as zircon.

Cathode heater 20 is supplied with current by a heater source of potential 28. Focusing electrodes 22 and 24 may have a frusto-conical configuration which cause a hollow, cylindrical electron stream 21 to be formed from electrons emitted by the cathode 16. Focusing electrodes 22 and 24 are maintained at a suitable potential with respect to the cathode 16 by an appropriate connection thereto. The oscillator is tuned by means of a voltage divider 30 which has an adjustable contact arm 32 to which the cathode 16 is connected. Voltage supply 34 is connected across the voltage divider 30, voltage supply 34 having its positive terminal connected to ground. Accelerating anode 26 may be grounded as shown.

Disposed coaxially within the envelope 12 in the direction of electron flow from the gun 13 there is shown a matching ferrule 36 connected over an antenna lead 38 to a conductive helix 40. A collector electrode 42 is disposed at the right end of the envelope 12 to intercept the stream electrons. In order to prevent secondary electrons from reaching the helix 40, collector 42 is maintained at a few hundred volts positive with respect to ground by a potential source 43 having its negative terminal grounded. Helix 40 with antenna lead 38 and matching ferrule 36 are all maintained at ground potential by a connection to accelerating anode 26.

At the right end of helix 40, a lossy material 44, e. g. a commercial preparation known as Aquadag, is deposited on the last few turns of the helix to prevent an undesirable type of self-oscillation. This self-oscillation may be produced by the reflection of microwaves traveling along the helix at the collector 42 and the subsequent reflection and regeneration of these signals at the electron gun 13.

The dielectric rod 18 extends through substantially the complete length of the helix 40. At periodic intervals along the rod 18, a plurality of conductive coils 46 is wound about the rod 18. The coils 46 are energized by a potential source 48, the leads extending through or along rod 18.

Outside the envelope 12, at its left end, rectangular output waveguide 50 is shown having a conductive sleeve 52 disposed about the envelope coextensive with the matching ferrule 36. Waveguide 50 also has a conventional shorted termination 54.

A plurality of solenoid windings 56 is positioned at regular intervals along and about the envelope to focus the hollow electron stream produced by the electron gun

13. The windings 56 are provided with magnetic shields 58 and are energized by a focusing source of potential 60. The windings 56 are disposed at the same axial positions of the coil 46 on dielectric rod 18. The coils 46 may be provided with magnetic cores not shown; however, such cores may be undesirable since they reduce the axial flux linking the cross-section of the electron stream. The windings 56 in cooperation with the coils 46 are designed to produce a variation of the axial flux, ϕ_z , having a variation with radius r , which may be of the type shown in Fig. 2 where r_s represents the radial position of an electron in the outer boundary surface of the hollow electron stream; r_i represents the radial position of an electron in the inner boundary surface; r_{s0} and r_{sM} are the maximum and minimum radii of r_s , respectively; r_{i0} and r_{im} are the maximum and minimum radii of r_i , respectively; and where r_v is the radius at which the axial flux density, B_z , and the flux linking the path of an electron, ϕ_z , are both equal to zero.

In the operation of the oscillator of Fig. 1, noise at the collector end of the traveling-wave tube 10 causes a backward-wave to be propagated along the helix 40. Mutual interaction of the electron stream produced by the electron gun 13 and the backward-wave is produced by keeping the ratio

$$\frac{r_{sM}}{r_{s0}}$$

near unity. As the stream enters the first electron lens which is produced by the left-hand winding 56 and its 30 associated coil 46 it is introduced at

$$z = -\frac{L}{2} \text{ with } \frac{dr_3}{ds} = \frac{dr_i}{ds} = 0$$

where L is the distance between lenses and z , which is equal to zero at the center of the left-hand winding 56, is distance along the stream 21. The magnetic field between r_{s0} and r_{i0} is produced by one winding 57 which opposes the field of an associated coil 45 in the stream. The fields produced by the windings 56 are then employed to overcome the space charge and centrifugal forces of an electron in an r_s orbit. The flux linking an inner electron, at a radial distance r_i , as it enters a lens will become substantial. Centrifugal force then carries it past the radius r where the field produced by a winding 56 will then refocus it. The inner electron will then have an angular velocity equal to zero when r_i again equals r_v . As the electron again enters the field of the succeeding coil 46, centrifugal force prevents the collapse of the inner boundary surface of the stream because the inner electron is caused to rotate.

In Fig. 3 another lens structure is shown which may be employed to give a suitable axial flux density variation with radius. Two axially polarized permanent magnets 130 and 132 are shown disposed concentrically about the hollow stream 21 with appropriately indicated magnetic poles. Both magnets 130 and 132 are hollow cylinders which may be of material having "hard" or permanent magnetic properties, e. g. an alloy commonly known by the trade name Alnico. Magnet 132, being the smaller of the two, is disposed concentrically within magnet 130. The external cylindrical magnet 130 is provided with two inwardly extending annular appendages or rims 131. The internal magnet 132 is likewise provided with annular appendages 133. The magnetization of the external magnet 130 must be greater than that of internal magnet 132 because the magnetic flux in the external magnet 130 is diverted through the internal magnet 132. A plurality of pairs of magnets such as magnets 130 and 132 would, of course, be employed at regular intervals along the hollow stream 21 to focus it.

As shown in Fig. 4, in order to prevent flux leakage in the employment of magnets such as magnets 130 and 132, an alternative embodiment of the invention may be used. There a magnetic electron lens is produced by

a cylindrical pole piece 140 of iron or other magnetic material having inwardly extending annular appendages or rims 142 surrounding two outer solenoid windings 144 and a central winding 146, the outer windings 144 providing aiding fields and the central winding 146 providing an opposing field. A plurality of such pole pieces and windings may again be positioned at regular intervals along the stream 21 to focus it. A radially varying magnetic field may thus be produced, the fields of the outer windings protruding into the center of the pole piece 140.

In order to produce a satisfactory design of the electron limit of the present invention it may be necessary to solve the motion equation of an electron. In the following development the meter-kilogram-second system of units is followed throughout. Before the motion equation can be solved, the axial flux density variation, B_z , in one of the electron lenses produced by a winding 56 and an associated coil 46 must be found. It will generally vary as a function of axial length, z , and radius, r as $B_z = f_1(z)f_2(r)$.

The electric field intensity E_s at r_s due to space charge is

$$25 \quad E_s = \frac{C_0(r_s^2 - r_i^2)}{2r_s \epsilon_0} \quad (1)$$

where C_0 is the charge and ϵ_0 is the permittivity of free space of 8.854×10^{-12} farad/meter.

The total force on an electron at r_s is

$$m \ddot{r}_s - mr_s \dot{\theta}_s^2 = -er_s \dot{\theta}_s B_{3z} + eE_s \quad (2)$$

where m is the mass of an electron or 9.12×10^{-31} kilograms, r_s is the radial acceleration of an electron in the outer boundary surface of the stream, θ_s is the angular velocity of the electron, B_{3z} is the flux density at r_s , and e is the charge of an electron or 1.59×10^{-19} coulomb. By substitution

$$40 \quad B_{3z} = f_1(z)f_2(r_s) \quad (3)$$

where $f_2(r_s)$ contains a reference to maximum field strength B_0 and radius r_v .

According to Busch's theorem, if no flux links the cathode 16,

$$45 \quad \theta_s = \frac{n\phi_s}{2\pi r_s^2} \quad (4)$$

where

$$n = \frac{e}{m}$$

$$\pi = 3.1416$$

$$55 \quad \phi_s = \int_0^{r_s} B_s dA$$

and

A is area

Then

$$60 \quad \theta_s = \frac{n\phi_s}{2\pi r_s^2} \quad (5)$$

where

$$65 \quad \phi_s = 2\pi f_1(z) \int_0^{r_s} r_s f_2(r_s) dr_s$$

By definition

$$70 \quad C_0 = \frac{I_0}{\pi(r_s^2 - r_i^2)(2\pi V_0)^{1/2}} \quad (6)$$

where I_0 is the stream current and V_0 is the stream voltage. Assuming

$$75 \quad C = \frac{nI_0}{2\pi \epsilon_0 (8n^3 V_0^3)^{1/2}} \quad (7)$$

and substituting Equations 5, 6 and 7 into Equation 2 using

$$r = 2nV_0 \frac{dr_3}{dz^2} \text{ because } \frac{dV_0}{dz} \approx 0$$

the following is obtained:

$$\frac{d^2r_3}{dz^2} = \frac{n^2\phi_{3s}}{4\pi r_3 V_0} \left(\frac{\phi_{3s}}{2\pi r_3^2} - B_{3s} \right) + \frac{C}{r_3} \quad (8)$$

By analogy

$$\frac{d^2r_i}{dz^2} = \frac{n^2\phi_{is}}{4\pi r_i V_0} \left(\frac{\phi_{is}}{2\pi r_i^2} - B_{is} \right) \quad (9)$$

where

$$\phi_{is} = 2\pi f_1(z) \int_0^{r_i} r_i f_2(r_i) dr_i$$

in that $B_{iz} = f_1(z) f_2(r_i)$, $f_2(r_i)$ also containing a reference to B_0 and r_i .

The correct lens spacing is dictated by the characteristics of the stream which it is desired to focus.

An approximate design procedure of the invention may be obtained by considering that the field of a neighboring lens may be omitted in the solution to Equations 8 and 9. It will be found that the distance between lenses should be larger than a certain number or constant, say $L \geq 6a$ where a may be a constant in the function, which depends on the magnetic field distribution, e. g. such as

$$f_i(z) = \frac{1}{1 + \frac{z^2}{a^2}} \quad (10)$$

$2r_{30}$ should be about equal to the inside diameter of the helix. For a given beam perveance, the maximum value of r_{10} or r_{1m} will be determined by the maximum perveance of the hollow stream. Generally r_{1m} should not be so small as to bring the stream outside the fields of the wave propagated along the helix 40.

The only three parameters for proper design which remain undetermined are C , which is proportional to the hollow stream perveance, B_0 and r_v . B_0 and r_v are both dependent upon C . With the use of an analogue computer, the trajectories of electrons having radii r_i and r_v may both be found by solving Equations 8 and 9 and by assuming different values for C , B_0 and r_v . From the trajectory plots in the solution of Equation 9, B_0 may be plotted as a function of r_v for a given lens spacing, say

$$\frac{L}{a} = 6$$

For the same lens spacing, from the trajectory plots in the solution to Equation 8, B_0 may again be plotted a number of times as a function of r_v for different conditions of C . The conditions for focus are then defined as the values of C which give values of B_0 and r_v that are identical to those found on the curve of B_0 versus r_v from the solution to Equation 9. For focus r_{sm}/r_{s0} may be plotted as a function of C . A value of C should be picked giving r_{sm}/r_{s0} near unity, and where C is large, e. g.

$$\frac{r_{sm}}{r_{s0}} = 0.8$$

if r_{sm}/r_{s0} decreases as C increases. From the other information known B_0 and r_v may be plotted as a function of C for the conditions of focus. Having selected a value for C from the curve of r_{sm}/r_{s0} versus C , B_0 and r_v and therefore the field strength and distribution produced by the windings 56 and the coils 46 may be determined.

What is claimed is:

1. In an electron stream-type tube, electron stream focusing apparatus comprising an electron gun for producing a hollow electron stream and for directing it along a predetermined rectilinear path, a plurality of outer electron lens devices, an inner electron lens device disposed within each of said outer electron lens devices, each asso-

ciated pair of said lens devices being disposed at periodic intervals along said predetermined path and arranged to develop a magnetic field to focus the inner and outer electrons of the hollow stream substantially at common focusing points disposed between adjacent associated pairs of said lens devices and spaced along said predetermined path, whereby the hollow beam remains substantially focused along said predetermined path, and the magnetic fields developed by said lens devices being such that the electrons on the inner boundary surface of the stream are deflected by magnetic and centrifugal forces causing them to move toward said common focusing points, whereby outward radial forces produced by said magnetic fields approximate the radial forces which would be exerted on said electrons by electron space charge if the beam were solid.

2. The invention as defined in claim 1, wherein said inner electron lens devices are disposed within the inner boundary surface of said hollow electron stream and said outer electron lens devices are disposed outside of the outer boundary surface of said hollow electron stream.

3. The invention as defined in claim 1, wherein all of said inner and outer electron lens devices are disposed outside of the outer boundary surface of said hollow electron stream.

4. In an electron stream-type tube, electron stream focusing apparatus comprising an electron gun for producing a hollow electron stream, means for directing said hollow stream along a predetermined path, a plurality of outer magnetic electron lens devices, and an inner magnetic electron lens device disposed within each of said outer electron lens devices, each associated pair of said lens devices being disposed at periodic intervals along said predetermined path and arranged to develop a magnetic field to focus periodically the electrons in both the inner and outer boundary surfaces of said hollow stream at common positions along said path disposed between adjacent associated pairs of said lens devices, whereby said hollow stream remains focused along substantially its entire length, the magnetic field developed by said lens devices being such that the electrons on the inner boundary surface of said hollow stream are deflected by magnetic and centrifugal forces causing them to move toward said common focusing positions.

5. In an electron discharge device, an electron stream focusing device comprising an electron gun for producing a hollow electron stream, means providing a plurality of magnetic electron lenses along a predetermined path, the axial magnetic flux density within a predetermined radius 50 in the planes of symmetry of said lenses being negative with respect to the axial magnetic flux density without said predetermined radius in said planes of symmetry, and means for directing said stream along said predetermined path through said lenses at a velocity to cause the electrons in the inner and outer boundary surfaces of said hollow stream to be focused periodically at the same axial positions along said path.

6. An electron stream focusing apparatus comprising an electron gun for producing a hollow electron stream, 60 means providing a plurality of magnetic electron lens devices spaced along a predetermined path, the axial magnetic flux within a predetermined radius in the planes of symmetry of said lens devices being in opposition to the axial magnetic flux without said predetermined radius 65 in said planes of symmetry, and means for directing said stream along said predetermined path through said lens devices, at a velocity to cause the radius of the inner boundary surface of said stream to vary about said predetermined radius.

7. In an electron stream-type tube, an electron stream focusing device comprising an electron gun for producing a hollow electron stream, a plurality of magnetic solenoid windings disposed at periodic intervals along a predetermined path for producing a plurality of magnetic electron lenses, a magnetic shielding member disposed about each

of said solenoid windings, a plurality of magnetic coils, each being disposed concentrically within one of said solenoid windings, whereby the axial magnetic flux density produced within a predetermined radius is negative with respect to that produced outside of said predetermined radius, and means for directing said stream along said predetermined path between said solenoid windings and said conductive coils at a velocity to cause the electrons in the inner and outer boundary surfaces of said hollow stream to be focused periodically at the same axial positions along said path.

8. In a traveling-wave tube having a slow-wave structure and an electron gun for producing a hollow electron stream, an electron stream focusing device comprising a plurality of magnetic solenoid windings disposed at periodic intervals along and about the slow-wave structure for providing a plurality of magnetic electron lenses, a magnetic shielding member disposed about each of said solenoid windings, a plurality of magnetic coils, each being disposed concentrically within the slow-wave structure and one of said solenoid windings, whereby the axial magnetic flux density produced within a predetermined radius is negative with respect to that produced outside of said predetermined radius, and means for directing the hollow electron stream through said electron lenses so as to pass between the slow-wave structure and said conductive coils at a velocity to cause the inner boundary surface of the stream to vary about said predetermined radius.

9. In a traveling-wave tube having a conductive helix for propagating microwaves and an electron gun for producing a hollow electron stream, an electron stream focusing device comprising a plurality of external axially polarized magnetic cylinders disposed about the helix at periodic intervals therealong, a plurality of internal magnetic cylinders having aiding internal fields, each of said

internal cylinders being disposed coaxially between one of said external magnetic cylinders and the helix, and means for directing the stream through the helix and through said cylinders at a velocity to cause the electrons in the inner and outer boundary surfaces of the stream to be focused periodically at the same axial positions along the helix.

10. In a backward-wave oscillator having a conductive helix for propagating microwaves and an electron gun for producing a hollow electron stream, an electron stream focusing device comprising a plurality of magnetic cylinders disposed about the helix at periodic intervals therealong, a central solenoid winding disposed within each of said magnetic cylinders outside of the helix, two adjacent solenoid windings disposed on each side of each central winding, said central winding producing a magnetic field in opposition to those of said adjacent windings, whereby the axial magnetic flux density produced at the central planes of symmetry of said magnetic cylinders within a predetermined radius is negative with respect to that produced at said planes outside of said predetermined radius, and means for directing the hollow electron stream through the helix and through said magnetic cylinders at a velocity to cause the inner boundary surface of the stream to vary about said predetermined radius.
